STOCKING

Julius Miran, Bronx, N. Y.

Application May 5, 1950, Serial No. 9,736

Term of patent 14 years

(Cl. D47—7)

To all whom it may concern:

Be it known that I, Julius Miran, a citizen of the United States of America, residing at 1721 Grand Avenue, Bronx, New York, in the county of Bronx and State of New York, have invented a new, original, and ornamental Design for a Stocking, of which the following is a specification, reference being had to the accompanying drawing, forming part thereof.

In the drawing:

Fig. 1 is a fragmentary side view of a stocking showing my new design;

Fig. 2 is a fragmentary rear view.

Fig. 3 is a bottom plan view.

Fig. 4 is a view on a smaller scale of an entire stocking.

I claim:

The ornamental design for a stocking, substantially as shown.

JULIUS MIRAN.
